RICHMOND E. REVALK, OF SAN FRANCISCO, CALIFORNIA.

AUTOMATIC RIBBON-REVERSE FOR TYPE-WRITERS.

1,177,442.

Specification of Letters Patent. Patented Mar. 28, 1916.

Application filed March 13, 1915. Serial No. 14,103.

To all whom it may concern:

Be it known that I, DUANE D. PHALEN, a citizen of the United States, residing in the city and county of San Francisco and State of California, have invented new and useful Improvements in Automatic Ribbon-Reverse for Type-Writers, of which the following is a specification.

This invention relates to ribbon mechanism for typewriting machines and particularly to an automatic reverse mechanism operative by the ribbon.

It is an object of my invention to provide in a typewriting machine a simple, light practicable and reliable automatically reversing mechanism operable by the writing ribbon through the instrumentality of the typewriter keys.

It is a further object to provide a mechanism for automatically reversing the ribbon travel, which may readily be installed upon the machine with the requirement of but very little alteration thereto and which is of few parts and inexpensive in construction.

The invention consists of the parts and the combination and construction of parts as hereinafter more fully described and claimed, having reference to the accompanying drawings, in which—

Figure 1 is a front elevation of a standard machine with the reversing mechanism installed and omitting one of the ribbon spools. Fig. 2 is a plan view of the mechanism with the space bar displaced forwardly, for illustration. Fig. 3 is a side elevation of the machine, partly in section, omitting the carriage, and showing the reversing device in section and detail. Fig. 4 is a perspective of the separated lever and slide. Fig. 5 is a detail section of the lever latch. Fig. 6 shows a modification of the eye-prong.

A indicates, generally, a standard, well known make of typewriter having a lower main frame 2 to which is pivoted at 3, a pair of arms 4 forming a part of a foldable carriage frame 5. Secured to this is a type-bar guide 6 in front of a carriage 7 movable along the carriage frame.

Suitably mounted on the main frame 2 for oscillation just below the carriage is a transverse spacer bar 9 which is actuated by the keys to the machine to operate the carriage escapement mechanism (not shown).

Mounted perpendicularly in the arms 4

are fixed arbors 10 upon which are loosely mounted spur gears 11 with elongated hubs 12 threaded at 13 to receive knurled nuts 14. These nuts are adapted to bind removable ribbon spools 15 firmly to the gear hubs 60 so that the spools will be turned by and with the respective gears.

My invention pertains to means for actuating the ribbon spool gears 11 and particularly to means for automatically reversing the direction of rotation of the gears so that the ribbon 16 connected to the spools will be wound alternately upon the spools. I utilize a ribbon having or formed with a shoulder, lug or abutment device 17 near 70 each of its ends. The ribbon spools are both locked on the gear hubs by the nuts 14 and the ribbon rove through guides 18 of ribbon cups 19 secured on the arms 4 and through a vibrator 20 adjacent the guide 6. 75

The invention comprehends means for alternately positively actuating first one and then the other gear 11 and is shown as comprising in one embodiment, a pair of worms or screws 21 for respective gears 11. The worms 21 are mounted upon the ends of an oscillating lever 22, Fig. 4, which is centrally pivoted at 23 to a convenient part of or on the carriage frame 5. The ends of lever 22 are slotted at 24 to receive screws 85 25 fast in the arms 4 upon which the lever ends rest and slide as it oscillates about its pivot 23. The function of the lever 22 is to carry the worms 21 alternately into and from mesh with its respective gear 11, so 90 that first one is driven to wind off the ribbon from the opposite reel and is then unmeshed and the other worm thrown into mesh and the ribbon travel reversed. The worms 21 are rotated by means of little 95 ratchet wheels 21' secured thereto and which are actuated by pawls 26 carried by the oscillating spacer bar 9.

While the worms and their gears may be meshed and unmeshed by any suitable means, I accomplish it by oscillating the carrier or lever 22 which is controlled and operated by the following means: On the lever 22 is slidably mounted a shifting coupler 27 with upwardly projecting spaced 100 prongs 28 having eyes 29 through which the ribbon 16 is rove. The coupler also has depending tongues or lugs 30 on opposite sides of the lever pivot 23 projecting in the path of operation of the spacer bar 9. 105

In operation, when the spacer bar is actuated or forced rearwardly by the operation of a character or space key, the bar 9 will strike either of the tongues 30 within 5 its path of action and so swing the lever 22 about its pivot 23 sufficiently to carry one worm in mesh and the other out of mesh. As the bar forces one tongue rearwardly the opposite tongue will swing forward and to 10 permit this the bar is notched at 31—31 these notches being spaced a distance less than the pitch of the tongues 30. When a ribbon shoulder 17 draws toward and engages the adjacent eye prong 28 of the sliding 15 coupler this will be shifted by the ribbon 16 to carry one tongue 30 into the plane of one notch 31, while the other tongue moves over clear of its coordinate notch 31 of the bar and thus stands in the path of 20 the bar 10. Fig. 2 shows the lineal relations of the tongues 30 to the notches 31 in the bar, which has forced the left-hand end of lever 22 rearward. As the ribbon 16 moves to the right its shoulder 17 will engage the 25 left-hand upright prongs 28 and shift the slideable coupler so that the right-hand tongue 30 will shift beyond the line of the slot and it will be pressed back by the next rearward action of the bar. Thus the lever 30 22 forms at once a bearing and a shifter for the worms 21, the sliding member 27 forming a momentary coupling device between the lever and the typewriter spacer bar, the coupler being controlled and actuated directly by the ribbon 16. As shown, as the 35 ribbon shifts the coupler and this is struck by the spacer the shifter lever unmeshes the coacting worm and gear of the winding spool and meshes up the worm and gear of the opposite spool which is then driven at each blow 40 of the respective ratchet pawl on the bar. The coupler is alternately shifted by the shoulders on the ribbon ends with the sequence that the bar strikes one of its tongues 30—30, 45 and therefore the lever is rocked to shift the worms.

Any simple form of detent latch may be employed to temporarily retain the shift lever in one or the other of its several positions and such device here consists of a 50 yieldably supported ball 33 (Fig. 5) in one of the arms 4, which engages spaced indents 34 in the bottom of the superposed end of the lever 22.

55 In Fig. 6 a hook-shaped eye 29 in a prong 28, of the coupler 27, is shown.

Having thus described my invention, what I claim and desire to secure by Letters Patent is—

60 1. In a typewriting machine, the combi-

nation of rotative carriers, ribbon spools secured on said carriers, a driver for each spool carrier, means operative by the keys of the machine for simultaneously disengaging one of the drivers from its respective 65 carrier and engaging the other driver with its carrier, means being controlled by the ribbon and including a shifting member carrying said drivers, and a sliding coupler mounted upon said member and actuated by 70 the ribbon.

2. In a typewriting machine, the combination of rotative carriers, ribbon spools each detachably secured on said carriers, a driver for each spool carrier, means operative by the keys of the machine for simultaneously 75 disengaging one of the drivers from its respective carrier and engaging the other driver with its carrier, means being controlled by the ribbon and including a 80 shifting member connected to said drivers, and a coupler mounted upon said member actuated by the ribbon, and engageable by a key operated part whereby the shifter is actuated. 85

3. In a ribbon reversing mechanism, in combination, spools for the ribbon, driving means for each of said spools, a lever carrying said driving means, and ribbon engaging devices carried by said lever and controlling the oscillation thereof for simultaneously moving said driving means into coactive relation with one of said spools and out of coactive relation with the other of 90 said spools. 95

4. A ribbon reversing mechanism comprising spools for the ribbon, driving means for said spools, a lever connected with said driving means, a coupler movably mounted on said lever, a key operated part, and means controlled by the ribbon for moving said coupler into engagement with said key operated part. 100

5. A ribbon reversing mechanism comprising spools for the ribbon, driving means for said spools, a pivoted lever carrying said driving means, a coupler slidably mounted on said lever, ribbon guiding devices carried by said coupler, a key operated part, and means on the ribbon engaging with said 105 guiding devices for sliding the coupler into cooperative relation with said key operated part.

In testimony whereof I have hereunto set my hand in the presence of two subscribing 115 witnesses.

DUANE D. PHALEN.
